UNITED STATES PATENT OFFICE.

EDWARD JACKSON, OF READING, PENNSYLVANIA, ASSIGNOR TO THE NOLDF AND HORST COMPANY, OF READING, PENNSYLVANIA, A CORPORATION OF PENNSYLVANIA.

STRIPING MECHANISM FOR CIRCULAR-KNITTING MACHINES.

Application filed May 16, 1923. Serial No. 639,303.

To all whom it may concern:

Be it known that I, EDWARD JACKSON, a citizen of the United States, residing at Reading, in the county of Berks and State of Pennsylvania, have invented certain new and useful Improvements in Striping Mechanism for Circular-Knitting Machines, of which the following is a specification.

My invention relates to circular knitting machines having vertical striping mechanism, and it consists in improved means for determinedly engaging different striping threads with different numbers of needles, as fully described in connection with the accompanying drawing.

Fig. 1 is a detail perspective view showing a single thread-guide and its relation to a grouping of needles, only a few of the circular series of the latter being indicated in connection with a fragmentary portion of the needle cylinder.

Fig. 2 is a diagrammatic front elevation indicating a needle grouping for a thread guide; and Fig. 3 is a cross-sectional view on the line 3—3 of Fig. 2, more clearly indicating the needle-engaging finger swing.

Fig. 4 indicates a multi-colored stripe produced by the needle grouping shown in Figs. 2 and 3.

My improvements relate to a circular knitting machine having a striping attachment of the type fully shown and described in Robinson Patents Nos. 1,357,253 and 1,357,254 of November second, 1920, the drawings merely indicating one such thread guide 11 in connection with a portion of a needle cylinder and a few adjacent needles, as sufficient to fully describe my invention. this guide having the usual socket bearing 12, and cam-actuated rollers 15 and 16; the stops for limiting the needle-engaging swings thereof not being shown, as any of the different means employed in said patents or others may be used as best suited to the requirement. The number of thread guides 11 employed, it will be understood, depend on the number of embroidery stripes desired, and each guide may be given like swings to produce similar stripes or may be varied to produce differing stripes as determined.

The thread-guide 11, for purposes of my invention, is formed with a plurality of thread-carrying fingers, each carrying a sep-

arate thread and adapted to swing in a fixed spaced arc around a determined group of adjacent needles 25 to engage their embroidery threads with such needles in the manner described in said Robinson patents, the needles being vertically movable in the equally spaced grooves of needle cylinder 18. In the drawings this guide is shown with three such thread-carrying fingers 20, 20, 20, spaced for and adapted to swing in equal arcs 21, 21, 21, embracing adjacent groups of one needle and three needles respectively, such construction producing a three part continuous stripe.

In order to vary the widths of the component parts of said stripe and enhance the appearance where contrasting colors are used in the respective fingers, I provide for differently grouping the needles 25 within the respective needle-engaging swings 21, 21, 21, of said thread-carrying fingers 20, 20, 20, the drawing showing a single needle in the center and three needles each in the outer group. These groups are formed as shown, by latterly bending the projecting hooked-end portions of certain needles 25 so as to bring them within the needle engaging swing of one of said thread carrying fingers 20; such bending having no harmful effect on the fabric as the sinkers equally distribute the yarn loops to the respective needles. This bending of the needles may be for the purpose of removing a needle from the swing of one finger 20 and bringing it within the swing of an adjacent finger, as in the case of needle 25^a; or it may be for the purpose of bringing a finger not included in any such swing within the swing of an end finger 20, as in the case of needle 25^b; or it may be merely to bring the hooked ends into closer relation so the arc of swing of the thread guide 11 may be only that required to engage such closed together group, as in the case of needles 25^c, 25^d. The thread guide 11 is properly set so that the needle-engaging swings 21, 21, 21 of its fingers 20, 20, 20 while equal, will each only engage the needles of one group.

In Fig. 4 I have indicated a fabric having a stripe produced by the needle arrangement shown in the drawings, *a*, *a* the outer portions being formed by the outer three-needle group with a central dividing portion *b* formed on the center needle, which should

preferably be of a contrasting color for best effect.

The number of thread guide fingers 20, may be of course varied as desired, as well as their spacings and their needle-engaging swings, in connection with different grouping of the needles and with various colored yarns, permits production of a great variety of color effects, and I do not desire to limit myself to the specific arrangement shown and described.

What I claim is:

1. A circular knitting machine comprising a thread guide having a plurality of fixedly-spaced thread-carrying fingers, means for imparting a determined needle-engaging swing to said guide, and a needle cylinder having a circular series of equally spaced reciprocating needles certain adjacent ones of which are bent laterally to closely group their thread-engaging ends.

2. A circular knitting machine comprising a thread guide having a plurality of

fixedly-spaced thread-carrying fingers, means for imparting a determined needle-engaging swing to said guide, and a needle cylinder having a circular series of equally spaced reciprocating needles certain adjacent ones of which have their projecting portions bent laterally to determinedly group their thread-engaging ends within the swing of said fingers.

3. A circular knitting machine comprising a thread guide having a plurality of fixedly-spaced thread-carrying fingers, means for imparting a determined needle-engaging swing to said guide, and a needle cylinder having a circular series of equally spaced reciprocating needles certain adjacent ones of which have their projecting portions bent laterally to determinedly vary the number of needles embraced by the swing of the several fingers.

In testimony whereof I affix my signature.

EDWARD JACKSON
